US00D625726S

(12) **United States Design Patent**
Crisp et al.

(10) **Patent No.:** **US D625,726 S**
(45) **Date of Patent:** **** Oct. 19, 2010**

(54) **COORDINATE INPUT DEVICE**

(75) Inventors: **Thomas Crisp**, Beaverton, OR (US);
Michael Keith Lemmon, Portland, OR (US); **Pierre Harper**, Portland, OR (US); **Kai Halsinger**, Portland, OR (US)

(73) Assignee: **Wacom Co., Ltd.**, Saitama (JP)

(**) Term: **14 Years**

(21) Appl. No.: **29/344,456**

(22) Filed: **Sep. 29, 2009**

(30) **Foreign Application Priority Data**

Apr. 28, 2009 (JP) 2009-009785

(51) **LOC (9) Cl.** **14-02**

(52) **U.S. Cl.** **D14/389**

(57) **CLAIM**

The ornamental design for a coordinate input device, as shown and described.

DESCRIPTION

FIG. 1 is a perspective view of a coordinate input device showing a new design;

FIG. 2 is a front elevational view of the coordinate input device;

FIG. 3 is a back elevational view of the coordinate input device;

FIG. 4 is a top plan view of the coordinate input device;

FIG. 5 is a bottom view of the coordinate input device;

FIG. 6 is a right side elevational view of the coordinate input device; and,

FIG. 7 is a left side elevational view of the coordinate input device.
